UNITED STATES PATENT OFFICE.

FERDINAND MORA CANDA, OF PLAINFIELD, NEW JERSEY.

PROCESS OF AND APPARATUS FOR FORGING BALLS.

1,204,127.

Specification of Letters Patent.

Patented Nov. 7, 1916.

Application filed February 23, 1915. Serial No. 9,844.

To all whom it may concern:

Be it known that I, FERDINAND MORA CANDA, a citizen of the United States of America, and a resident of Plainfield, in the county of Union and State of New Jersey, have invented a certain new and useful Process of and Apparatus for Forging Balls, of which the following is a specification.

10 My invention relates to a process of and apparatus for forging metal objects, particularly balls, and as a process comprises the shearing of a billet into blanks, the end-pressing of such blanks between cup dies 15 with consequent compression of the metal in one direction, and expansion of the metal in other directions, to fill the dies, the spreading out of excess metal into a fin, and the shearing of the fin, all of which operations are performed at one heat, and preferably in one press.

As an apparatus my invention comprises forging means comprising shearing means, cup forging dies, and fin shearing means, 25 all operated by a single reciprocating member; also means for automatically advancing a billet to the first mentioned shearing means; also means for freeing the forged object from the cup dies; and various other 30 features, all as hereinafter described and pointed out in the appended claims.

The object of my invention is to provide an improved method of, and improved means for, producing forged metal balls and 35 other forged articles, without reheating, with a minimum of handling, and at minimum cost.

I will now proceed to describe my invention with reference to the accompanying 40 drawings, and will then point out the novel features in claims.

In the drawings: Figure 1 shows a front elevation of a forging press provided with dies, shearing means, etc., and automatic 45 feed means in accordance with my invention; the press itself being of familiar type. Fig. 2 shows a side elevation of the press, portions of the press being broken away. Fig. 3 shows a transverse 50 vertical section through the cup dies and associated parts on a larger scale than the preceding views; the section of Fig. 3 being on a plane parallel to that of Fig. 2. Fig. 4 is a detail side elevation of a mechanism for freeing the forged objects from 55 the cup dies. Fig. 5 shows a vertical sec-

tion of the dies, shears, etc., of the press, this section being taken on the center line of the press, on a plane parallel to that of Fig. 1. Fig. 6 shows a top view of the lower dies and associated parts of the press, the upper dies and associated parts having been omitted. Fig. 7 shows a side elevation of the two shear blades employed together with a section of a billet between those shear blades. Fig. 8 is a more or less diagrammatic view showing the forging press and its feed table associated with a rolling mill and the feed tables thereof, whereby the metal is rolled from the ingot into a bar of 70 the required size for the blanks and thence transferred to the press and converted into balls, all at one heat.

My invention is particularly intended to facilitate the making of large metal crusher 75 balls—say for example, balls of three inches diameter and over—such as are employed in crusher mills, but the method and apparatus herein described are also applicable to the formation by forging of other objects; projectiles, for example. Heretofore large balls, projectiles, etc., have usually been made under the steam hammer and by a large number of blows of the hammer, reheating of 80 the ball blanks being required after shearing 85 of such blanks from the billets, in order that the blanks may be at a proper forging temperature when placed under the hammer. Such reheating is expensive, particularly 90 since it requires considerable handling of 95 the blanks, and the taking of them to and from the reheating furnace, and it also involves possibility of injury to the metal. Furthermore, the process of hammering a blank into ball shape under the steam hammer is somewhat expensive, requiring skilled 100 labor, and requiring repeated turning of the body of metal in process of formation into a ball, from sixty to eighty blows being required. By the method and apparatus herein described, these objections are avoided, for the billet is sheared, the sheared blanks thereby produced are pressed into ball shape, and the fin resulting from such pressing is sheared off, all within one press and by successive single operations performed by a single reciprocating member of that press; and such operations are performed by means in such close proximity to one another, and in such rapid sequence, that no reheating 110 is required. Preferably, these operations are performed by means of a forging press, the

action of which as compared with that of a steam hammer or other mechanical hammer, is particularly advantageous; for while the speed of operation of such a press is 5 practically that of a steam hammer or other mechanical hammer, yet such a press applies its pressure to the metal being forged somewhat gradually as compared with a hammer, the metal being given time to flow so as to 10 fill the dies, whereby by a single stroke of the press a blank may be converted into a ball or like object, whereas when forming a ball or like object by means of a hammer, a succession of blows are required.

15 Referring now to the accompanying drawings, and at first to Figs. 1, 2, 5, 6 and 7, numeral 1 designates the ram of an ordinary forging press, 2 the head thereof, and 3 the anvil thereof. I will not describe the construction and operation of the press in detail, as such presses are well known. It is sufficient to say that in the operation of such a press as illustrated, the ram 1 rises and falls under control of an operator, so raising 20 and lowering the head 2, and with it any die or dies carried by that head; the operation of the press being quite rapid, the press nevertheless exerting a pressing action upon the metal, as distinguished from a hammering action.

30 Figs. 5 and 6 show the various dies, etc., with which the press is provided, according to my invention. The head 2 and anvil 3 of the press are provided with die blocks 4 and 35 5 respectively, in or to which are secured cup dies 6 and 7 (shown, in this case, as of a form suitable for forming balls), also with fin-shearing ring dies 8 and 9. To these die blocks are also secured shear blades 10 and 40 11, shown in side elevation in Fig. 7. In coöperative relation with the shear blades a feed table 12 provided with the usual carrying rolls 13, is provided; the purpose of this feed table being to deliver the billet 45 automatically to the shearing blades; and the upper die block 4 is further provided with an adjustable stop 14 whereby the length of the pieces cut off from the billet by the shear blades is determined.

50 15 designates a billet mounted upon the feed table. It will be apparent that at each rise of the press ram, as soon as the upper shear blade 10 is raised upon the billet 15, that billet will be advanced by the feed 55 table until the front end of the billet encounters the stop plate 14. Upon the next descent of the press ram, the shear blade 10, coöperating with the shear blade 11, will shear off a portion of the billet, which portion or blank will then drop upon the table portion 16 of the lower die block 5. In this table portion of the die block is a groove 17 provided to facilitate the insertion of tongs to grasp the blank thus sheared off. Upon 60 the next rise of the ram a workman will

grasp the blank 18 with tongs, and, lifting that blank and turning it upright, or on end, will place it within the lower cup die 7. The next descent of the press ram will cause the cup dies 6 and 7 to press that blank into ball form, excess metal, if any, (and it is usually necessary to provide for some excess of metal) flowing out into the grooves 19 provided in the adjacent faces of the upper and lower press dies, the result being 75 the formation of an equatorial fin upon the partly formed ball 20.

In order to free the partly formed ball 80 from the cup dies 6 and 7, and also to facilitate the transfer of such partly formed ball from the cup dies to the fin-shearing dies, 8 and 9, plungers 21 and 22 are provided in suitable bores formed in the cup dies 6 and 7 and in the die blocks 4 and 5. Without confining myself to automatic means, or to any particular means, for actuating these plungers 21 and 22, I have illustrated, particularly in Figs. 3, 4 and 6, convenient means for actuating such plungers comprising pivoted levers 23 and 24 located in convenient slots in the die blocks 3 and 4, and bearing against the outer ends of the plungers 21 and 22 respectively; also rods 25 and 26 operated by the ram 1 as hereinafter described, for operating said levers 23 and 24. The rod 25 is provided with an adjustable abutment 27 whereby, as said rod is lifted, the outer end of the lever 24 is lifted, so raising the plunger 22, and lifting the ball 20, permitting a workman to introduce a 95 fork underneath the equatorial fin of this ball; and then, as the plunger 1 continues to rise, the workman transfers this ball to the fin cutting die 9, the fin of the ball resting upon the die 9. Rod 25 passes through an ear 28 of the press head 2; and said rod 25 is further provided with a loose abutment 29 adapted to be engaged by that ear 28 as the press head 2 rises; also with a fixed abutment 30; and between abutments 29 and 30 there is a stiff spring 31. It will be seen, 100 that as the press head 2 rises, with the ram 1, the ear 28 will engage the abutment 29, and, the lift being transmitted through spring 31 to abutment 30, will raise rod 25, 105 110 and the abutment 27 on that rod engaging lever 24 and so actuating plunger 22.

The rod 26 which actuates lever 23 is supported by the stationary anvil block 3, and is provided with an adjustable abutment 32 and a movable abutment 33, between which abutments there is a stiff spring 34. As the press head 2 rises, carrying with it the lever 23, this lever 23 engages the abutment 33, and, owing to the resistance offered by the 115 spring 34, that lever 23 is pressed down, with reference to the rising press head 2, so forcing down, with reference to that rising press head, the plunger 21.

Ordinarily, the plunger 21 is not required,

since rarely, if ever, will the ball adhere to the upper die 6, and lift therewith; but the plunger 21 and means for operating the same is provided as a precaution and will 5 force the ball out of the die 6, if such ball adheres to such upper die 6.

The ball having been transferred to the shearing die 9, upon the next down stroke of the press rain the annular die 8, co-operating 10 with the annular die 9, shears off the equatorial fin, the ball, thereby completed, falling through the die 9 into a delivery passage 35 provided in die 5 and in the press anvil 3, and rolling off to any convenient point of delivery. Conveniently, 15 the upper die block 4 is provided with a portion 36 which will force the formed ball down through die 9 into this delivery passage, as the fin is sheared off. It will thus be seen that the completed balls 20 deliver themselves, and I purpose to extend the delivery passage 35 by means of a trough 37 (Fig. 2) which trough will have such length that the balls, as they travel 25 down it, will cool until by the time they reach the end of that trough they will be sufficiently cold to drop into cars. If the press must be so located that it is not convenient to have the cars, to receive such 30 balls, at a sufficient level below the press, a suitable elevator may be provided to raise the balls to such height that they may fall from that press, into another trough (which, with the elevator is functionally a continuation 35 of the trough 37) and from such other trough the balls may roll until cooled sufficiently to be dropped into the car without injury.

It will be understood that each of the 40 three operations of cutting off a blank, pressing a blank into ball form, and shearing the fin from a formed ball, is ordinarily performed at each stroke of the press; in other words, at each downward stroke of the 45 press, three bodies of heated metal undergo treatment in stages which succeed one another. The workmen are required to perform only very simple operations indeed, viz.—the turning of the blank 18 upright 50 and the placing of it between the cup dies, and the transfer of the formed ball, with fin thereon, to the fin cutting dies; and since these operations are simple and easily performed, and since the workmen are required 55 to move the metal a very short distance only, the press may operate with great rapidity; in fact, at a rate of between ten and twenty strokes a minute. The operation is so rapid that the metal cools but little between the successive operations. In 60 fact, it is practicable to receive the billet directly from the usual billet-forming rolling mill upon the table 12, and by that table 12 deliver the billet to the shear blades 65 10 and 11, and thence to perform the vari-

ous operations of the press upon such billet, without any reheating whatever. This is illustrated in Fig. 8, wherein 38 designates an ordinary rolling mill (shown in this case as a three-high mill) and 39 designates the 70 usual feed tables of such mill, one of these tables being arranged to discharge the rolled billet upon the feed table 12 of the press. It will be readily apparent that by such co-operative arrangement of rolling mill, feed 75 tables, and press, it is quite practicable to roll an ingot to a billet and thence transfer it to the feed table 12, and so to the press, and convert the billet into balls, all without reheating.

While I have described my process and apparatus with particular reference to the formation of balls, I do not intend thereby to limit my process to the formation of balls only, but to the contrary may employ my 85 process, and the described apparatus, for the formation of projectiles and other compact metal bodies, the dies, of course, having such form as adapts them for the formation of the objects to be produced.

What I claim is:—

1. The herein described method of forging balls and like objects, which comprises cutting heated billets into blanks, pressing each blank as produced, to form, between 95 suitable dies, and then cutting off the fin produced by such dies, the several operations of producing the blanks, pressing such blanks into form, and cutting off the fins, being performed each as a single operation and all at one heat.

2. Means for forging balls and the like, comprising in combination cutting off means for cutting successive blanks from a body of metal, pressure forming means for 105 pressing such blanks to form, and fin cutting means, and a single operating device for all of said three means, whereby the several operations of cutting off, pressing to form, and removing the fin, may be performed in one heat and by successive transfer of blanks from the cutting off means to the pressure means, and thence to the fin cutting means.

3. Means for forging balls and the like, comprising in combination cutting off means for cutting successive blanks from a body of metal, pressure forming means for 115 pressing such blanks to form, and fin cutting means, and a single operating device for all of said three means, whereby the several operations of cutting off, pressing to form, and removing the fin, may be performed in one heat and by successive transfer of blanks from the cutting off means to the pressure means, and thence to the fin cutting means, and means for freeing the formed article from the pressure means.

4. Means for forging balls and the like, comprising in combination cutting off 130

- means for cutting successive blanks from a body of metal, pressure forming means for pressing such blanks to form, and fin cutting means, and a single operating device for all of said three means, whereby the several operations of cutting off, pressing to form, and removing the fin, may be performed in one heat and by successive transfer of blanks from the cutting off means to the pressure means, and thence to the fin cutting means, and a gravity delivery passage through which the formed articles may escape upon removal of the fins therefrom.
5. Means for forging balls and the like, comprising in combination cup dies and fin-shearing dies, and a single operating means for operating said dies, one of the fin cutting dies having an aperture through it of a size adapted to permit the passage through that die of the formed object after the fin has been removed from such object.
6. Means for forging balls and the like, comprising in combination cup dies and fin-shearing dies, and a single operating means for operating said dies, one of the fin cutting dies having an aperture through it of a size adapted to permit the passage through that die of the formed object after the fin has been removed from such object,
- 20 30 and a delivery chute arranged to receive the formed objects as they drop through such apertured die.
7. Means for forging balls and the like, comprising in combination a rolling mill adapted to roll ingots and the like into bars of a cross section suitable for the formation

of balls therefrom, cutting means and pressing means adapted to cut such bars into suitable blanks and to press same to ball-form, automatic feeding means arranged to deliver the bars to said cutting means, and automatic feeding means arranged to deliver the rolled bars from the rolling mill to said first mentioned feeding means.

8. The herein described method of forging balls and like objects, which comprises hot rolling a metal ingot into a blank-bar, cutting said bar into blanks, and pressing each blank to ball-form as produced, the several operations of rolling the heated ingot, cutting the resulting bar into blanks, and pressing such blanks into form, being performed all at one heat.

9. The herein described method of forging balls and like objects, which comprises hot rolling a metal ingot into a blank-bar, cutting said bar into blanks, and pressing each blank to form as produced, the several operations of rolling the heated ingot, cutting the resulting bar into blanks, and pressing such blanks into form, being performed all at one heat, and the cutting and pressing operations being performed each as a single operation.

In testimony whereof I have signed this specification in the presence of two subscribing witnesses.

FERDINAND MORA CANDA.
